CAN PERFORATOR AND DISPENSER

Victor F. Gouch and George V. Gouch,
Chicago, Ill.

Application March 13, 1941, Serial No. 383,198

2 Claims. (Cl. 221—23)

This invention relates to perforator and dispenser attachments to be applied to standard cans containing liquids to be dispensed therefrom.

An important object of our invention is to provide a device of the aforementioned character which has a piercing element provided with helically-shaped locking means to engage a can top after perforation, and secure the same in removably locking engagement therewith.

Another object of our invention is to provide an attachment of the aforementioned character having spout dispensing means similar to oil can construction.

Another object of our invention is to provide piercing means, and auxiliary piercing and locking means which will secure the invention removably to the top of a standard can.

Another object of our invention is to provide a device of the aforementioned character which will pierce a can and is also provided with force pump means in order to dispense the contents of the can by the auxiliary aid of air pressure.

Another object of our invention is to provide a device of the aforementioned character which will be easily and readily attachable to a standard can and which will be easily removable therefrom, yet will stay in a fixed relationship during the period of dispensing the contents from the said can, yet a device which is practical, efficient, useful in its operation, and of such simple construction that it will lend itself to economical manufacture in quantity production.

Other features and objects of our invention will become apparent from the accompanying drawings and the ensuing description wherein like numerals are used to designate like parts and in which:

Fig. 1 represents a longitudinal view of a standard can and a form of our invention attached thereto.

Fig. 2 is an enlarged partial cross-sectional view looking in the direction of the line 2—2 of Figure 1.

Fig. 3 is a transversal cross-sectional view on the line 3—3 of Figure 1.

Fig. 4 is an enlarged fragmentary cross-sectional view taken on the line 4—4 of Figure 3.

Fig. 5 is a bottom plan view of our invention as shown in Figure 1.

Fig. 6 is a front plan view of the conventional type of oil can used at the present time.

Fig. 7 is a longitudinal cross-sectional view showing another form of our invention used in connection with larger sizes of cans containing

liquid contents to be dispensed therefrom and which require pressure in order to dispense the liquid therefrom.

Fig. 8 is a transversal cross-sectional view on the line 8—8 of Figure 7.

Fig. 9 is a side elevation partly in section of a modified form of our invention in order to best show the arrangement of the piercing and locking point illustrated in Figure 10.

10 Fig. 10 is a fragmentary bottom plan view of Figure 9.

Fig. 10a is a bottom plan view of the member 60 shown in Figure 7 and forming a part of our invention.

15 Fig. 10b is a transversal cross-sectional view on the line 10—10 of Figure 2.

In general practice especially in machine shops and other similar establishments where oil has to be used to great extent for machining operations or for lubrication purposes, the conventional can shown in Figure 6 is utilized and is comprised of body 29 and spout 30, and a threaded portion 31 which serves to secure the spout 30 to the body of the can removably so that it may be filled with oil.

The tendency in general practice, has been that these cans are dropped and caused to be broken and smashed from time to time from use and hence require replacement continually. 30 These cans are comparatively expensive considering the invention we have provided, and it is our intention to replace abuse of this type of oil-can structure by replacing it with our invention which is cheaper to manufacture and produce, and may be used interchangeably with cans of standard manufacture.

Another disadvantage, also, in the use of cans shown in Figure 6, is that when a can is selected by a user, a few squirts of oil usually have 40 to be expelled therefrom, by forcing the bottom portion of the can or manipulating it so as to eject forcefully a few drops, so that the user may determine whether it is the proper grade of oil. Considerable oil is thus wasted and hence lost.

Our invention, on the other hand, in being attached to a standard can which is of rigid construction, will permit our use of the bottom portion of the can for manipulation to eject forcefully from the spout, oil which is necessary. The can utilized will always have imprinted thereon as it comes from the manufacturer, the imprinted matter carrying the grade of oil and the type of oil and the uses to which it may be applied. Therefore it will save considerable oil, which at 50 the present time is used for purposes of inspec-

tion in order to determine whether the oil contained in a can of the type shown in Figure 6, is satisfactory oil needed for a particular operation.

Our method of dispensing oil from a unit such as we created will also enable a manufacturer to keep his product before the user at any and all times, which incidently is good business and good advertising. Ordinarily, cans of this type have to be pierced, the oil is then poured into standard oil cans such as shown in Figure 6, and soon the grade of the contents becomes unknown and its particular uses.

Referring now, particularly, to Figures 1, 2, 3, 4, and 5, a preferred form of our invention is indicated. In those views the wing-nut member 13 is shown with a recess portion 14 in order to receive a gasket 15 which may be made of cork or of a type of rubber which is impervious to oil and which will not deteriorate when coming in contact with oil.

The wing-nut member 13 is provided with a counterbore 19 to which is secured a conventional oil spout 11 being of a tapered construction and having a tapered recess or opening 12 terminating in a fine spout so as to permit oil to be ejected therefrom in minute quantities as lubrication conditions may necessitate. To the wing-nut member 13 is secured the blade member 16 which is provided with a pointed portion 24 and an enlarged portion in an upward direction provided with the off-set portions 25 and 26 creating the rib structure for reinforcing this blade so as to make it rather rigid for the perforating action which it has to perform. The upper portion of the blade 16 is provided with an opening 27 and terminates in two spiral portions 17 which are provided with the bent portion 28 which may be riveted or spot-welded to the inner recess 14 of the wing-nut member 13. The bore 19 after the gasket 15 is secured thereto leaves a resultant communicating recess 18 for the oil to pass thru to the spout recess 12.

The device may be grasped rigidly between the fingers and palm of the hand and forcefully brought to bear down on the top surface 79 of a can 20 having its top and bottom portions 19 and 23, double seamed as at 21, and thus the perforating point 24 will make a slotted opening 32 in the top 79 of the can 20. Then by virtue of the wing-nut 13 the device is given a quarter turn, in which event the helical portion 17 tends to lock the device firmly in sealed position. When this is done, the can 20 may be inverted and by pressing the bottom 23 one or more times, the oil 22 will be forcefully ejected from the spout opening 12.

We wish to stress the structural function of the portions 17 which are given the same pitch or lead and are equivalent in action to what is known as a double thread. The pitch of each portion 17 being the same and being positioned a diametral distance permits the said portions to act simultaneously in effecting the sealing of the device against the top of a can.

The illegible written matter designated 34 indicates the writing on the label of the can which will disclose to users after a cursory inspection the grade of oil, the manufacturers name, and thus serve an advertising function as well as an informational function in giving the user proper notice of the product about to be utilized.

Figures 7 and 8 show another form of our invention as utilized with a larger type of can 33, and embraces the use of auxiliary pressure means for forcing the liquid contents of the can thru

without inverting the can. The structure generally comprises two strap members 37 which are formed as indicated in order to take adjustably a series of varied diameters, and shapes of cans such as square, hexagonal, etc. These strap members are connected articulately at one point by the screw 40 and a nut 41 and are secured to the pump unit 48 which is provided with the fork member 50, being further secured adjustably at the opposite ends by virtue of the screw 38 and the nut 39. It may be noted that the strap members 37 preferably possess a ribbing structure 67 so as to lend rigidity and thus make for a firm gripping of the can 33. The top of the can is seamed as at 35 and so is the bottom 36.

The liquid contents of the can are designated 66 and it may be noted that the piercing point 65 of the tube 64 reaches almost to the top of the can 33. The oil level is below the point 65 and being out of contact with the opening 68 will be fed thru the opening 70 later to be described.

To elucidate further the structure comprising our invention, the forked member 50 is secured articulately by virtue of the screw 49. The member 45 has an eye portion 46. The upper portion of the clamping unit is comprised of the member 44 having an anchoring point 42 and a handle portion 43 for conveniently carrying the assembled unit of our invention and a can once they are assembled in place firmly together. The member 44 and the member 45 have right and left hand threads in order to match the right and left hand threaded portions 76 and 77 of the turn buckle 75, which is provided in order to take in adjustably various heights of cans.

The piercing unit 65 is encased in a tapered housing 69 having an oil out-let 10. The combination of the unit 65 and 69 are properly and frictionally secured in the core opening, and bore, and counter-bore designated 81, connecting with the bore 88 and further connecting with the bore 61 in the casting 60 which has a female threaded extension 59, reinforced to the remaining portion of the casting 60 by virtue of rib 63. The upper portion of the casting is counter-bored as at 89 in order to provide a proper retaining portion for the gasket member 74 which is to seal the unit with the can bottom 36 after it has once been pierced. The turn buckle serves to hold this unit firmly and fixedly in assembly, yet it may be removed after the contents of the can have been completely dispensed.

The casting 60 is also provided with a boss 71 into which fits the reinforced end 72 of the flexible tubing 73 terminating in a suitable spout, the flexible tubing serving the purpose of convenient manipulation to portions of machinery and equipment that is not readily accessible to a rigid form of spout.

The pressure assembly is comprised of a pump housing 48 having a hub extension 49 in order to give proper guide to the piston plunger 51 having also a knurled knob 52 or other suitable manipulation knob. The plunger rod 51 is secured to a leather cup washer 53 which has thin side walls and which tends to flare out on a downward stroke of the knob 52 yet tends to collapse on an upward stroke, to admit air to come thru into the passage 55 past the piston 53 when on the downward stroke, the side portions of the cup 53 spread out to forcefully compel the air to proceed thru the tube 58 and thru the opening 61 and then follow the arrows thru the outlet 68 accumulating pressure at the top causes

the oil level 68 to be forced downward and the oil to drain thru the opening 73 and out into the tubing 73 for actual application where needed.

The tapered spring members 54 having smaller coils 47 the smallest being at the top and nesting within the leather cup piston 53 serves to return the plunger upwardly after it is once depressed in a downward direction. Several manipulations of this plunger will accumulate sufficient air pressure in the top of the can in order to dispense the liquid contents within the can. As the contents of the can are gradually dispensed, air automatically takes its place within the container, and therefor just a slight pressure is required to be built up within the can in order to forcefully eject the liquid therefrom.

The pressure casting 48 is secured to the tubing 58 by virtue of a flanged coupling 56, threaded at 62, secured to the casting 48, and having a reduced hub 57 which is frictionally secured to the tubing member 58. Altho, leather has been specified for the piston or cup 53, any other similar suitable material may be utilized for the purpose.

In Figures 9 and 10 we show a slightly modified form as compared to our invention depicted in Figures 1, 2, 3, 4 and 5. In this form we indicate a wing-nut member 13, having a recess 14 and a suitable gasket member 15 to secure to the top 79 of a can 20. To the lower portion of the wing-nut member 13 in a suitable counterbore is secured by a drive fit method a piercing member 78 having a pointed portion 86 for piercing a can and having a further counterbored portion at the top designated 84 and an oil connecting feed recess 85 which connects the recess 12 in the spout 11 to the inner portion of the can.

The locking means utilized in this particular instance comprises the piercing blades 80, spot-welded to the wing-nut member 13 at the point 83, being helically shaped as at 81 the same as the portions 17 of the form of invention illustrated in Figure 1, having a cam actuating and locking surface which will aid in locking removably this unit to the top portion of a can after it has been pierced.

The members 80 are provided with pointed portions 82 which pierce the can forming recesses 90 which when the wing-nut member is

turned one eighth or one quarter turn, will lock the entire unit in assembly. The gasket 15 being of sufficient resiliency to keep the assembly under tension until the contents of the can have been dispensed and it is desired to remove the unit to be applied to another can. The oil flows from the inner portion of the can thru the communicating recesses 85 into the recess 84 and out thru the terminus of the recess 12 or the spout 11.

We believe we have described in rather succinct terms the nature and operation of our invention and described and illustrated fully, preferred forms of our invention, and inasmuch as our invention is susceptible of many modifications, alterations, and improvements, we reserve the right to all such modifications, alterations, and improvements that come within the spirit and scope of our invention, the accompanying drawings and within the purview of the foregoing description; our invention to be limited only by the appended claims.

Having thus disclosed and revealed our invention what we claim as new and desire to secure by Letters Patent is:

- 25 1. A device of the character described comprising, knob means, spout means secured to the said knob means, can slotting means secured to the said knob means, the said slotting means terminating in multiple thread helically-shaped cam locking and sealing means adapted to secure removably the said device to a can, and gasket means secured to the outer lower portion of said knob means.
- 30 2. A device of the character described comprising, knob means, conically-shaped spout means secured to the central portion of said knob means, cam slotting means secured to the said knob means in juxtaposed relationship to said spout means, the said slotting means comprising, a triangularly-shaped element terminating at its base in multiple-thread helically-shaped portions, the transverse cross-section of said slotting means composed of two straight and offset portions interconnected by an oblique portion, the said multiple-thread helically-shaped portions being secured to the said knob means, and gasket means secured to the face of said knob means.
- 35 3. A device of the character described comprising, knob means, spout means secured to the central portion of said knob means, cam slotting means secured to the said knob means in juxtaposed relationship to said spout means, the said slotting means comprising, a triangularly-shaped element terminating at its base in multiple-thread helically-shaped portions, the transverse cross-section of said slotting means composed of two straight and offset portions interconnected by an oblique portion, the said multiple-thread helically-shaped portions being secured to the said knob means, and gasket means secured to the face of said knob means.
- 40 4. A device of the character described comprising, knob means, spout means secured to the central portion of said knob means, cam slotting means secured to the said knob means in juxtaposed relationship to said spout means, the said slotting means comprising, a triangularly-shaped element terminating at its base in multiple-thread helically-shaped portions, the transverse cross-section of said slotting means composed of two straight and offset portions interconnected by an oblique portion, the said multiple-thread helically-shaped portions being secured to the said knob means, and gasket means secured to the face of said knob means.
- 45 5. A device of the character described comprising, knob means, spout means secured to the central portion of said knob means, cam slotting means secured to the said knob means in juxtaposed relationship to said spout means, the said slotting means comprising, a triangularly-shaped element terminating at its base in multiple-thread helically-shaped portions, the transverse cross-section of said slotting means composed of two straight and offset portions interconnected by an oblique portion, the said multiple-thread helically-shaped portions being secured to the said knob means, and gasket means secured to the face of said knob means.
